(57) **CLAIM**

I claim the ornamental design of the dual handled shovel, as shown and described.

DESCRIPTION

FIG. 1 is a perspective view of the dual handled shovel of my new design;

FIG. 2 is a reduced scale side elevation view thereof, the opposite side being a mirror image thereof;

FIG. 3 is a top plan view of FIG. 2;

FIG. 4 is a bottom plan view of FIG. 2;

FIG. 5 is a front elevational view of FIG. 2;

FIG. 6 is a rear elevational view of FIG. 2;

FIG. 7 is a sectional view take along the line 7—7 of FIG. 3;

FIG. 8 is a perspective view of a first modification of the dual handle shovel of my new design;

FIG. 9 is a reduced scale side elevational view of FIG. 8, the opposite side being a mirror image thereof;

FIG. 10 is a top plan view of FIG. 8;

FIG. 11 is a bottom plan view of FIG. 8;

FIG. 12 is a front elevational view of FIG. 8;

FIG. 13 is a rear elevational view of FIG. 8; and,

FIG. 14 is a sectional view taken along line 14—14 of FIG. 10.
